INKING DEVICE.

Rupert L. Greenleaf, Auburn, Maine

Application March 15, 1940, Serial No. 324,175

4 Claims. (Cl. 101—305)

This invention relates to an improved inking device for use with stamping and embossing machines of the type shown in my application, Serial No. 294,941, filed September 14, 1939.

One object of the invention is to provide an inking device which will be operative for uniformly inking the striking surface of a die so that said die will be properly inked preliminary to a marking operation.

Another object of the invention is to provide an inking device which will ink the die in such a manner that there will be no surplus of ink on the die, with the result that a clean line will be assured and waste of ink obviated.

A further object of the invention is to provide an inking device which will include an ink roll which is mounted so that, when the striking head employed is moved rearwardly, said inking roll will be released and will travel over the face of the die as the striking head is moved forwardly for completely and effectively inking said die.

A further object of the invention is to provide an inking device including improved mounting mechanism which will be operative for holding the ink roll in an inoperative position except at such time when said ink roll is actually inking the face of the die.

A still further object of the invention is to provide an inking device employing improved latch mechanism for releasing the ink roll so as to permit it to engage the face of the die for an inking operation.

Still another object of the invention is to provide an inking device employing improved means for mounting the ink roll, said means being operative for urging the ink roll into engagement with the face of the die during an inking operation.

And a still further object of the invention is to provide a device of this character employing rails on the die holder, which rails will be effective for automatically returning the ink roll to inoperative position after the face of the die has been inked, said rail including means for automatically releasing the ink roll preliminary to a die inking operation.

And another object of the invention is to provide an inking device employing an ink well for inking the ink roll when necessary.

Other objects of the invention will be made known as the description proceeds.

In the drawings:

Figure 1 is a perspective view of a marking machine and showing my improved inking device

as it would appear in inoperative position after a die inking operation.

Figure 2 is a side elevation showing the marking machine striking head in an intermediate position with the ink roll of my inking device in engagement with the die.

Figure 3 is a side elevation showing the marking machine with the striking head in its rear-most position and showing, in section, the release dog in engagement with the latch for releasing the ink roll preparatory to an inking operation, and

Figure 4 is an enlarged detail vertical sectional view showing the method of mounting the plungers which support the ends of the ink roll.

Referring now to the drawings wherein, as will be seen, similar reference numerals designate similar parts throughout the several views, the numeral 1 indicates in general a marking machine of the type shown in my pending application heretofore referred to. The marking machine 1 includes a frame 2 which is preferably formed as a single unit casting. The frame 2 includes a work-supporting table 3 and a platform

4, said platform being disposed in a parallel plane above that of the work-supporting table 3. As will be noted, the work-supporting table extends substantially half the length of the frame, while the platform extends substantially the other half of the length of said frame. Feet 5 are formed on the opposite ends of the frame and are apertured for receiving fastening devices. A vertically extending shoulder 6 is defined between the work-supporting table 3 and the platform 4. Side walls 7 and 8 are provided for the frame 2.

Associated with the frame 2 is a striking head 9 to which is removably connected the die holder 10. The die holder 10 supports a die which is to be engaged with the upper surface of work

11 on the work-supporting table 3. Pairs of connecting rods 12 and 13 operatively connect the striking head 9 with the frame 2. As the construction of the striking head, the connecting rods, and the frame are set forth fully in the pending application heretofore mentioned, it is not believed necessary to discuss this construction in more detail in this application. My improved inking device includes an ink roll 14 which is formed of sponge rubber or other suitable material. The ink roll 14 is mounted above the platform 4 at the forward end thereof and near the shoulder 6. The ink roll 14 is mounted on a shaft 15 which extends throughout the width of the frame 2 and past the side walls 7 and 8.

Mounted on the opposite ends of the shaft 15 are

rollers 16 which are rotatably engageable with tracks 17 on the side edges of the die holder 10. It will be understood that the rollers 16 will roll along the tracks 17 when the striking head is shifted forwardly for effecting a stamping or embossing operation. Small rollers 17 are carried on the corresponding inner ends of the track 17 and engage the rollers 16 so as to reduce wear and provide smoother operation for the rollers 16 on the track 17. Outwardly extending trunnions 18 are formed on the rollers 16 axially thereof. These trunnions are engageable with the latch mechanism, to be described in more detail hereinafter.

In order to mount the ink roll, I employ plungers 19 and 20. The plungers 19 and 20 are of identical construction so that a description of one will suffice for both. As seen in Figures 1, 2 and 4 of the drawings, the plungers are mounted in the platform 4 at the forward end thereof adjacent the shoulder 6. The plunger 20 is typical and includes a stem 21 which has a counterbored upper end which is internally threaded to define a socket 22. The lower end of the stem 21 extends through a boss 23 on the platform 4 and into the frame beneath said platform. A flange 24 is fitted on the stem, near its lower end, and serves a two fold function of limiting upward travel of the stem and of providing a seat for the upper end of a coil spring 25. The coil spring 25 is mounted in a guide cylinder 26 which extends throughout the height of the frame. Screwed into the socket 22 is a supporting screw 27 which is formed with an arcuate upper end 28. The upper end 28 receives the shaft 15 of the ink roll 14 at a point between the end of said ink roll and the inner surface of the roller 16.

It will now be seen that the plungers 20 effectively support the ink roll in operative position. The springs 25 will urge said plungers upwardly for urging the ink roll into engagement with the under surface of the die on the die holder during an inking operation. The position of the ink roll on the plungers 20 may be adjusted by temporarily removing the ink roll from the screws 27, and then rotating said screws to the desired position with respect to the stems.

In order to retain the plungers in inoperative position, in which position the ink roll will be retained except when actually inking the face of the die, I provide latches which are shown generally at 29. Two of the latches 29 are employed, one on each of the side walls 7 and 8 of the frame. As will be seen by referring to the drawings, the latches are mounted on the side walls near the shoulder 6 and directly beneath the trunnions 18. Inasmuch as the latches are of identical construction, a description of one will be sufficient. A typical latch includes a base 30 which is substantially rectangular in shape. The base is held in place on the side walls of the frame by means of screws 31. A portion of the upper end of the base 30 is turned outwardly at a right angle to define a bracket 32. An adjusting screw 33 is extended through the bracket. A post 34 is mounted on the base near its upper corner and serves to mount one end of a spring 35. A latch member 36 is associated with the base 29 and is pivotally mounted thereon by means of a pin 37, said pin extending through the lower end of said member. The spring 35 has its opposite end connected with the latch member, near its mid portion, by means of a pin 38. It will be seen that the spring 35 urges the latch member forwardly toward the adjusting screw 33. At its

upper end, the latch member is formed with an arcuate latch face 39 which is shaped to receive a portion of one of the trunnions 18.

As seen in Figure 3 of the drawings, the rails of the track 17 are each provided with depending pivoted dogs 40. The dogs are limited against forward movement by pins 41 which are extended into the rails. It should be understood that the dogs 40 will extend laterally so as to be in the same longitudinal path with the upper end of the latch members 36.

In order to provide means for inking the ink roll 14, when necessary, I employ an ink trough 42 which is of U-shaped formation. The ink trough is provided with end walls 43 and 44 which are formed with bearing slots 45. The bearing slots receive the shaft 15 of the ink roll 14 for permitting said ink roll to have a portion thereof immersed in ink carried in the trough. In order to ink the ink roll, it is only necessary to rotate said roll in the trough until said ink roll is inked throughout its circumference. The operation of my improved inking device will now be described in more detail.

After the work 11 has been placed on the work-supporting table 3 of the frame 2, the striking head 9 is shifted rearwardly to the position shown in Figure 3 of the drawings. In this position, the dogs 40 will engage the upper ends of the latch members 36 for releasing said latch members from engagement with the trunnions 18. When this takes place, the springs 25 will urge the stems 21 upwardly, with the result that the ink roll will be urged upwardly into engagement with the forward end of the die holder 10. As the striking head is swung upwardly and forwardly, as shown in Figure 2, the plungers will retain the ink roll in engagement with the face of the die on the die holder, for effectively inking said die. As the striking head is further moved forwardly, it will begin to swing downwardly. As the striking head moves downwardly and forwardly, the ink roll 14, with the plunger 20, will be forced downwardly against the tension of the springs 25. It will, of course, be understood that the rollers 16 will roll along the tracks 17 while the ink roll is inking the face of the die. The tracks 17 are of sufficient length so that, when the striking head swings clear from above the platform 4, the tracks will have urged the rollers downwardly to such a position that the latch members 36 will engage the trunnions 18 for retaining the ink roll in inoperative position. In other words, as heretofore mentioned, the ink roll will be in the position shown in Figure 1 at all times, except when actually inking the face of the die. Movement of the ink roll into and out of operative positions is entirely automatic and is controlled by the movement of the striking head and the die holder. It should be understood that, if desired, but one of the latches 29 may be employed. The use of two of said latches will assure uniform holding action for the opposite ends of the ink roll.

As the matter of inking the ink roll 14 has been described hereinbefore, it is not thought necessary to describe it further. It is accordingly believed that the construction and operation of my improved inking device will be thoroughly understood from the foregoing description.

Having thus described the invention, what is claimed as new is:

1. A device of the class described including, in combination with a marking machine having a

striking head, a frame, means swingingly connecting the striking head with the frame, a die holder having tracks, and a die on the die holder, an ink roll, plungers operatively connecting the ink roll with the frame, means for resiliently mounting the plungers, a latch for holding the ink roll in a retracted position, and a dog on the track of the die holder, said dog being engageable with the latch upon rearward swinging movement of the striking head for releasing the ink roll whereby said ink roll will be urged to engage the face of the die during forward swinging movement of the striking head, further forward movement of said striking head shifting said ink roll to retracted position and in engagement with the latch.

2. In an inking device, in combination with a frame, a striking head, means operatively connecting the striking head with the frame, a die holder on the striking head and having a track and a dog on the track, an ink roll having a shaft, rollers on the shaft, said rollers being engageable with the track, means resiliently mounting the ink roll on the frame and normally urging the ink roll toward an extended position above the frame, and a latch carried by the frame and having a latch member engageable with the ink roll for retaining the ink roll in a retracted position near the frame, said striking head being shiftable for engaging the dog with the latch member for freeing the ink roll whereby said roll will be urged to engage the die on the die holder for inking said die holder during forward movement of the striking head, further forward movement of said striking head shifting said ink roll downwardly for engagement with the latch member as the striking head is moved clear of the ink roll.

3. In combination with a marking machine having a striking head, a frame, means swingingly connecting the striking head with the

frame, a die holder on the striking head, and a die on the die holder, said striking head being movable from an inoperative position above the frame forwardly to a stamping position and rearwardly to a position for inking, an ink roll on the frame, means for resiliently mounting the ink roll, means for retaining the ink roll in lowered retracted position, means on the die holder and engageable with said last mentioned means for releasing the ink roll whereby said ink roll will engage the face of the die as said striking head is moved forwardly toward a stamping position, and means for urging said third mentioned means into engagement with the roll for relatching the roll after the striking head has moved past said roll toward operative position.

4. In combination with a marking machine having a striking head, a frame, means swingingly connecting the striking head with the frame, a die holder having tracks, and a die on the die holder, said striking head being movable from an inoperative position above the frame to a retracted position for inking and also being movable to a stamping position, an ink roll, means movably connecting the ink roll with the frame, means for normally urging the ink roll upwardly from the frame, means for holding the ink roll in a lowered retracted position against the tension of said last mentioned means, means on the track of the die holder and engageable with said last mentioned means upon rearward swinging movement of the striking head for releasing the ink roll whereby said ink roll will be urged to engage the face of the die during forward swinging movement of the striking head, and means urging the third mentioned means to relatching position upon further forward movement of the striking head for relatching the roll in lowered retracted position.

RUPERT L. GREENLEAF.
